UNITED STATES PATENT OFFICE.

GEORGE W. SCHILLING, OF PHILADELPHIA, PENNSYLVANIA.

DEVICE FOR REMOVING GEAR-WHEELS, &c.

1,268,285.

Specification of Letters Patent.

Patented June 4, 1918.

Application filed October 19, 1917. Serial No. 197,385.

To all whom it may concern:

Be it known that I, GEORGE W. SCHILLING, a citizen of the United States, residing at Philadelphia, in the county of Philadelphia, 5 and State of Pennsylvania, have invented certain new and useful Improvements in Devices for Removing Gear-Wheels, &c., of which the following is a specification.

One object of my invention is to provide 10 a device for removing gear wheels, pulleys, couplings, etc., from shafts, and which can be operated easily and quickly.

A further object is to so construct my invention that it may be applied and operated 15 without injuring the shaft to which it is applied or the article which is to be removed from the shaft.

Another object is to make my improved 20 device of a simple and durable construction which is portable.

These objects, and other advantageous 25 ends which will be described hereinafter, I attain in the following manner, reference being had to the accompanying drawings in which—

Figure 1 is a front elevation of my improved device illustrated together with a shaft and gear wheel and showing the parts in their operative position ready to be operated to remove said gear wheel from the shaft,

Fig. 2 is an end view of Fig. 1 looking in the direction of the arrow *x*,

Fig. 3 is an end elevation of Fig. 1 looking 35 in the direction of the arrow *y*,

Fig. 4 is an enlarged view of a plunger and centering pin which form parts of my invention,

Fig. 5 is an end view of Fig. 4,

40 Fig. 6 is a longitudinal elevation of one of two cross levers which form a part of my invention,

Fig. 7 is an end view of Fig. 6, and

Fig. 8 is a fragmentary section taken on 45 the line 8—8 of Fig. 2 showing the position which the parts assume when a filling block is inserted to project the plunger a greater distance out of the head than shown in Fig. 1.

50 Referring to the drawings, 1 represents a shaft having a gear wheel 2 thereon, said gear wheel being fixed to the shaft by means of a key 3 as is the usual custom of attaching a gear wheel to a shaft. A metallic head

55 4 includes a hub 5 and four radial arms 6, 7, 8, and 9. The outer ends of the arms 6

and 7 have bolts 10 and 11 respectively extending therethrough and these bolts are screw threaded for a portion of their length and provided with nuts 12 and 13.

Links or plates 14 and 15 are pivoted on the respective bolts 10 and 11 and are secured thereon by the nuts 12 and 13. These links 14 and 15 at their opposite ends have bolts 16 and 17 extending therethrough which are 60 also threaded through a portion of their length and have nuts 18 and 19 which engage the links 14 and 15, as clearly shown in Figs. 1 and 2.

Two cross levers 20 and 21 each have holes 70 22 adjacent their opposite ends and through which the opposite end portions of the bolts 11 and 17 and 10 and 16 extend. Thus the cross levers 20 and 21 are respectively in alinement with the links 14 and 15. The 75 cross levers 20 and 21 are held upon the bolts by nuts 23, said nuts being designed to engage recessed portions 24 formed in the outer surface 25 of the cross levers. Each of the cross levers 20 and 21 has an 80 elongated convex or outwardly curved surface 26 which is designed to engage the surface 27 of the gear wheel 2, as clearly shown in Figs. 1 and 3.

The arms 8 and 9 serve as guiding arms 85 and are located to the rear of the links 14 and 15. These guiding arms have guiding surfaces 28 which are curved in arcs concentric with the axes of the respective bolts 10 and 11, as clearly shown in Fig. 2. These 90 guiding surfaces 28 terminate in recesses 29 so that the bolts 16 and 17 will be guided by and confined adjacent the guiding surfaces 28 and the recesses 29 form pockets to limit the outward swing of the plates 14 and 15 on the bolts 10 and 11 as pivots.

The hub 5 has a cylindrical hole 30 in which is slidably mounted a plunger 31. This plunger with the exception of an angular cut-out portion 32 is cylindrical and 100 slidably fits the cylindrical hole 30, as clearly shown in Fig. 1. The cut-out portion 32 provides a shoulder 33 and also permits room to prevent keys on exceptionally small shafts to pass within the cylindrical 105 hole 30 so as to permit the complete withdrawal of the gear or other article from the shaft, as will hereinafter be fully explained.

The plunger 31 has a cylindrical hole 34 in which is slidably mounted a centering pin 35 which has a conical end 36 which is designed to engage the center hole 37 in the

- shaft 1. Centering holes as illustrated in 37 are usually provided in the ends of shafts for receiving an instrument to ascertain the speed of the shaft.
- 5 The centering pin 35 is backed by a coiled spring 38, thus the centering pin, being resiliently pressed, will not injure or disfigure the centering hole 27 of the shaft. The centering pin 35 is cut away throughout a portion of its length, as shown at 39, and the limiting screw 40 is inserted through the plunger 31 so as to be engaged by a shoulder 41 formed by said cut-out portion 39 of the centering pin.
- 10 The hub 5 has a screw-threaded hole 42 in which is mounted a comparatively heavy screw 43. The hole 42 leads into the cylindrical hole 30 so that the screw 43 can engage the inner end of the plunger 31 and causes the latter to be moved longitudinally within the hub 5. A retaining set screw 44 extends into the hole 30 and is designed to be abutted by the shoulder 33 of the plunger 31. Thus the retaining screw 44 prevents 25 the plunger 31 from accidentally falling out of the hub 5 but permits relatively longitudinal movement between the plunger 31 and the hub 5, as will be described hereinafter.
- 20 The arms 6 have holes 45 extending therethrough either of which is adapted to receive a lever 46. This lever 46 is adapted to extend to the floor or any other stationary object and permits the nuts 12, 13, 18, and 19 to be turned without the rotation of the entire head 4.
- 25 In the operation of my invention it will be readily understood that by turning the nuts on the respective bolts, the head 4 and cross levers 20 and 21 will be moved toward each other causing the plunger 31 to abut the end of the shaft 1, and since the convex surfaces 26 of the cross levers 20 and 21 engage the surface 27 of the gear 2, the gear will 30 be forced longitudinally along the shaft 1 and finally removed from the end of the shaft. In the use of my invention it is preferable to first start the gear wheel 2 by the rotation of the nuts 12, 13, 18, and 19 and 35 after the gear has been started in its movement from the shaft it is merely necessary to turn the screw 43 so that it will engage the end of the plunger 31; this will cause a relative movement between the head 4 and the plunger 31, and the gear can be easily removed by the action of the screw 43.
- 40 It is understood of course that the initial movement of the gear 2 longitudinally of the shaft requires greater power than after the gear has been initially moved; hence the bolts and nuts may be used to initially move the gear and afterward the screw 43 can be used and, with a single operation the gear can be entirely removed.
- 45 If an extremely wide face gear or a long
- coupling is to be removed, a filling block 47 can be interposed between the inner end of the plunger 31 and the inner end of the cylindrical hole 30, as clearly shown in Fig. 8. To permit the entrance of this filling 70 block 47 a cavity 48 is formed through the hub, as clearly shown in Figs. 2 and 8.
- By providing the cross levers 20 and 21 with the convex engaging surfaces 26 various degrees of leverage can be obtained 75 since the convex surfaces fulcrum on the surface 27 of the gear 2 or a similar surface of any other article which it is desired to remove. Furthermore by providing the guiding arms 8 with the guiding surfaces 28 80 the bolts 16 and 17 can be swung into positions attaching the circumference of the gear wheel, as clearly shown in Fig. 2, and thereby secures a direct leverage at points adjacent the gear.
- 85 I preferably make the bolt holes 22 in the cross levers 20 and 21 slightly larger than the diameter of the bolts 10, 11, 16, and 17 so that the cross levers are free to rock on their convex surfaces 26, as clearly shown 90 in Fig. 1. Furthermore the bolt holes in the arms 6 and 7 and in the links 14 and 15 are also preferably made slightly larger than the bolts to permit the bolts to extend at slight angles according to the direction 95 of pull and position of the cross levers 20 and 21. Thus the parts can adjust themselves in accordance with the movement of the nuts on the bolts.
- 95 My invention can be easily operated by 100 one man since the nuts 12, 13, 18, and 19 can be successively turned or if desired the nuts 23 can also be turned, and as above stated after the gear has been initially moved then it can be quickly removed 105 directly by the single screw 43.
- 100 While I have described my invention as taking a particular form, it will be understood that the various parts of my invention may be changed without departing from the 110 spirit thereof, and hence I do not limit myself to the precise construction set forth, but consider that I am at liberty to make such changes and alterations as fairly come within the scope of the appended claims.
- 110 Having thus described my invention, what I claim as new and desire to secure by Letters Patent is:
- 115 1. A device of the character described including a head; clamping bolts carried by the head; and a cross lever carried by said bolts, said head and said cross lever being movable relatively to each other through the medium of said clamping bolts, substantially as described.
- 120 2. A device of the character described including a head; clamping bolts carried by the head; and a cross lever carried by said bolts, said head and said cross lever being movable relatively to each other through the 125
- 130

- medium of said clamping bolts, said cross lever including an elongated convex engaging surface, located between the points of connection of said bolts with said latter cross lever, substantially as described.
3. A device, adapted to remove an article from a shaft, including a head having a hole therein; a plunger within said hole and adapted to abut the end of the shaft; means for engagement with a surface of said article opposite said end of the shaft; and means relatively to each other to cause said first means to move the article relatively to the shaft, substantially as described.
4. A device, adapted to remove an article from a shaft, including a head having a hole therein; a plunger within said hole and adapted to abut the end of the shaft; means for engagement with a surface of said article opposite said end of the shaft; and means relatively to each other to cause said first means to move the article relatively to the shaft; and means for moving said plunger longitudinally of said hole within the head, substantially as described.
5. A device, adapted to remove an article from a shaft, including a head having a hole therein; a plunger within said hole and adapted to abut the end of the shaft; means for engagement with a surface of said article opposite said end of the shaft; means for moving said head and said latter means relatively to each other to cause said first means to move the article relatively to the shaft; said plunger including a centering pin for engagement with a centering hole in said end of said shaft; and a spring forming a resilient backing for said centering pin, substantially as described.
6. A device, adapted to remove an article from a shaft, including a head having a hole therein; a plunger within said hole and adapted to abut the end of the shaft; means for engagement with the surface of said article opposite said end of the shaft; means for moving said head and said latter means relatively to each other to cause said first means to move the article relatively to the shaft; means for moving said plunger longitudinally of said hole within the head; and means for limiting the longitudinal movement of said plunger within said head, substantially as described.
7. A device, adapted to remove an article from a shaft, including a head; means on said head for engaging the end of the shaft; cross levers adapted to engage a surface of said article opposite to said end of the shaft; and clamping bolts operatively connecting said head and said cross levers, substantially as described.
8. A device, adapted to remove an article from a shaft, including a head; means on
- said head for engaging the end of the shaft; cross levers; and clamping bolts connecting said head and said cross levers, said cross levers having elongated convex surfaces for engagement with a surface of said article remote from said end of the shaft, substantially as described.
9. A device, adapted to remove an article from a shaft, including a head having a hole therein; a plunger within said hole and adapted to abut the end of the shaft; cross levers having elongated convex surfaces for engagement with a surface of said article remote from said end of the shaft; and clamping bolts connecting opposite ends of said cross levers with the head, substantially as described.
10. A device, adapted to remove an article from a shaft, including a head having a hole therein; a plunger within said hole and adapted to abut the end of the shaft; cross levers having elongated convex surfaces for engagement with a surface of said article remote from said end of the shaft; clamping bolts connecting opposite ends of said cross levers with the head; and a screw fitting within said head and adapted to move said plunger relatively to the head to increase the distance between said head and said end of the shaft, substantially as described.
11. A device, adapted to remove an article from a shaft, including a head having a hole therein; a plunger within said hole and adapted to abut the end of the shaft; means for engagement with the surface of said article opposite said end of the shaft; and means for moving said head and said latter means relatively to each other to cause said first means to move the article relatively to the shaft, said head having a cavity therein whereby filling material may be interposed between the inner end of said plunger and the inner end of said hole, substantially as described.
12. A device, adapted to remove an article from a shaft, including a head; clamping bolts secured in said head and extending substantially in the direction of the length of said shaft; links pivotally secured to said head; clamping bolts carried by said links and extending substantially in the direction of the length of said shaft; means on said head for engagement with an end of said shaft; and cross levers carried jointly by respective bolts on the head and on said links, said cross levers being adapted to engage a surface of said article remote from said end of the shaft, substantially as described.
13. A device, adapted to remove an article from a shaft, including a head; clamping bolts secured in said head and extending substantially in the direction of the length of said shaft; links pivotally secured to said head; clamping bolts carried by said links and extending substantially in the direction of the length of

- of the length of said shaft; means on said head for engagement with an end of said shaft; and cross levers carried jointly by respective bolts on the head and on said links, said cross levers having elongated 40
5 convex surfaces extending between their connecting bolts and adapted to engage a surface of said article which is remote from said end of the shaft, substantially as described.
- 10 14. A device, adapted to remove an article from a shaft, including a head having a hub and arms projecting from the hub; means carried by said head for abutting an end of 45
15 said shaft; clamping bolts supported by certain of said arms and extending substantially in the direction of the length of said shaft; links pivoted on each of said clamping bolts; other bolts carried by said links; the other of 50
20 said arms being adapted to be slidably engaged by said links and having guiding surfaces for said latter mentioned bolts; and cross levers carried jointly by respective 55
25 bolts on said first mentioned arms and said links, said cross levers being adapted to engage a surface of said article remote from said end of the shaft, substantially as described.
15. A device, adapted to remove an article from a shaft, including a head having a hub and arms projecting from the hub; means carried by said head for abutting an end of 60
30 said shaft; clamping bolts supported by certain of said arms and extending substantially in the direction of the length of said shaft; links pivoted on each of said clamping bolts; other bolts carried by said links; the other of 65
35 said arms being adapted to be slidably engaged by said links and having guiding surfaces for said latter mentioned 70
40

bolts; and cross levers carried jointly by respective bolts on said first mentioned arms and said links, said cross levers being adapted to engage a surface of said article remote from said end of the shaft; said second mentioned arms having recesses therein providing pockets for the second mentioned bolts and thereby limiting the pivotal movement of said links in one direction, substantially as described. 45

16. A device, adapted to remove an article from a shaft, including a head; means on said head for engaging the end of the shaft; cross levers adapted to engage a surface of said article opposite to said end of the shaft; clamping bolts connecting said head and said cross levers; and means for engagement with said head, and an adjacent stationary article whereby the nuts of said bolts can be rotated without rotating said head, substantially as 50
55 described. 60

17. A device, adapted to remove an article from a shaft, including a head; means on said head for engaging the end of the shaft; cross levers adapted to engage a surface of said article opposite to said end of the shaft, 55
60 clamping bolts connecting said head and said cross levers; and a lever for engagement with said head and an adjacent stationary article whereby the nuts of said bolts can be rotated without rotating said head, substantially as 70
75 described.

In testimony whereof I have signed my name to this specification in the presence of two subscribing witnesses.

GEORGE W. SCHILLING.
